UNITED STATES PATENT OFFICE.

NELSON D. CLARK, OF CHICAGO, ILLINOIS, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,316,426.

Specification of Letters Patent. Patented Sept. 16, 1919.

Application filed August 22, 1917. Serial No. 187,691.

To all whom it may concern:

Be it known that I, NELSON D. CLARK a citizen of the United States, residing at Chicago, in the county of Cook, State of Illinois, have invented certain new and useful Improvements in Presser-Feet for Sewing-Machines, of which the following is a description, reference being had to the accompanying drawing and to the figures of reference marked thereon.

The invention relates to new and useful improvements in presser feet for sewing machines, and more particularly to a presser foot used in connection with a two-needle machine for covering previously-formed seams.

An object of the invention is to provide a relatively stationary means operating upon the fabric in advance of the needles and on opposite sides of the seam for stretching said fabric prior to the applying of the covering stitches.

In the drawings, which show by way of illustration one embodiment of the invention,

Figure 1 is a view of the forward end of a sewing machine having my improved presser foot applied thereto;

Fig. 2 is a plan view of a portion of the work arm showing the feed dog and the looper;

Fig. 3 is a view partly in side elevation and partly in section through the presser foot;

Fig. 4 is a bottom plan view of the presser foot, showing in broken lines the position of the material as the stitches are applied thereto;

Fig. 5 is a sectional view on the line 5—5 of Fig. 3;

Fig. 6 is a front view of the presser foot, also showing the position of the needles and the material;

Fig. 7 is a sectional view through joined fabric sections, showing the covering stitches applied thereto.

The invention is directed to a presser foot

which is adapted to be used in connection with a two needle machine forming covering stitches. It has been customary in the art to join two fabric sections by a line of through-and-through stitches passing through said sections slightly back from the edges thereof. The sections are then turned out flat or into substantially the same plane and the joined edges passed through a sewing machine having two needles, which are disposed so as to pass down through the fabric section adjacent the joined edges and on opposite sides thereof.

Cooperating with the two needles is a looper which lays a looper thread across the raw edges of the seam and covers the same. In covering a seam of this character, it is desirable that the sections of fabric should be flattened as much as possible, and the present invention is directed to means which is normally stationary, so far as the feeding movements of the fabric are concerned, which means operates to stretch the fabric sections in advance of the needles and hold the sections stretched until the covering stitches have been applied thereto.

Referring more in detail to the drawings, I have shown my improved presser foot as applied to a sewing machine having a cylindrical work arm 1, an overhanging arm 2 in which a needle bar 3 reciprocates. The needle bar carries two needles, 4 and 5. Cooperating with the two needles beneath the work support is a looper 6. This looper is of the thread-carrying type and the looper enters both needle loops, so the looper thread will be concatenated with both needle thread loops and thus connect the two needle threads. The material is fed up the work arm by means of the feed dog 7.

In Fig. 7 of the drawings, I have shown two fabric sections indicated at F and F', which have been united by a line of stitching s. The fabrics are superposed upon each other and this line of stitching passed through the superposed edges. After these

edges are united, then the fabric sections are turned out into the position shown in Figs. 6 and 7. The present invention is directed particularly to means for stretching or pulling these two fabric sections, so as to flatten the joined edges as much as possible prior to the covering of the same.

The material is held on the work support by a presser foot 8 carried by a presser bar 9. The presser foot is formed with two needle openings 10 and 11 adapted to receive the needles 4 and 5 respectively. Said presser foot on its under face is also formed with a projecting keel 12. The fabric sections after they have been turned out as above described, are passed underneath the presser foot. The keel will run in the seam or between the fabric sections where they are joined, so as to direct the previously formed seam between the two needles 4 and 5.

The presser foot is formed with an opening 13 and with a bridge portion 14, which spans the opening and is attached to the upper surface of the presser foot.

Located in the opening 13 is a shoe or yielding member 15. This shoe has a stem 16 extending up through the bridge portion. Said stem has an opening 17 in the upper end for a spring 18. The spring is attached to the presser foot and is so arranged as to normally depress the stem and the shoe carried thereby until the spring strikes the upper surface of the bridge portion 14.

The under face of this shoe or yielding member 15 is formed with sets of ribs 19 and 20. The ribs 19 and 20 are oppositely inclined rearwardly and away from a center plane passing between the two needles. It will be noted that this yielding shoe is located between the needles and the keel and coöperates with the front end of the feed dog 7. The feed dog 7 has two spaced forwardly projecting parts 7^a between which the shoe operates. The adjacent side faces of the parts 7^a are beveled off at 7^c to prevent pinching the fabric between the stretching members and feed surfaces. Each rib is formed with its front face substantially vertical and its rear face inclined, as clearly shown in Fig. 5 of the drawings.

As the material passes under the presser foot, this yielding shoe bears on the material. The ribs 19 will engage one section of the fabric, while the ribs 20 will engage the other section. Owing to the inclination of these ribs, as the material is fed under the foot by the feeding mechanism of the sewing machine it will be stretched or the sections drawn in a direction away from each other, thus flattening the previously formed seam. The stretched sections will pass under the foot, across the needle-holes in the presser foot without being released, and the two needles will enter and cover the previously formed seam of the fabric sec-

tions while thus stretched. It will be noted that this yielding shoe does not move with the feed dog in its feeding movements, although it may yield independently of the presser foot, so as to maintain a pressure 70 against the fabric sections at all times regardless of the position of the presser foot, except, of course, when the presser foot is raised to its extreme upper limit for the purpose of inserting the material under- 75neath the same.

While I have described the invention as residing in a presser foot having certain structure it will be understood that the auxiliary foot operating to stretch the fabric 80 may be otherwise supported than by the presser foot. An essential feature of the invention consists in the inclined ribs extending in opposite directions from the central line and coöperating with the feeding 85 mechanism which moves the material across the ribs for stretching and flattening the same.

It is obvious that minor changes in the details of construction and the arrangement 90 of parts may be made, without departing from the spirit of the invention as set forth in the appended claims.

Having thus described my invention, what I claim as new and desire to secure by Letters Patent, is:—

1. The combination of a work support, feeding mechanism, a stitch forming mechanism, a presser foot, and devices carried by said foot and disposed directly above and 100 coöperating with said feeding mechanism to stretch the fabric passing under said foot, said devices being disposed in advance of said stitch forming mechanism.

2. The combination of a work support, 105 feeding mechanism, a presser foot having a guiding fin at its forward end, and devices carried by said foot and coöperating with said feeding mechanism to stretch the fabric passing under said foot, said devices being respectively disposed on opposite sides of a line coincident with the major axis of said fin.

3. The combination of a work support, feeding mechanism, a presser foot, and vertically yieldable devices, carried by said foot and disposed directly above and coöperating with said feeding mechanism to stretch the fabric passing under said foot.

4. The combination of a work support, a 120 stitching mechanism including a pair of needles and a thread carrying looper coöperating therewith, a feeding mechanism, a presser foot, and devices carried by said foot and disposed directly above and coöperating with said feeding mechanism to stretch the fabric passing under said foot, said devices being respectively disposed on opposite sides of a line passing centrally between said needles.

5. The combination of a pair of needles, a looper coöperating with said needles, a feeding mechanism, a work support, a presser foot, and a yielding member engaging the fabric in advance of the needles, said yielding member having ribs disposed so as to stretch the fabric prior to the stitching thereof.
6. The combination of a pair of needles, a looper coöperating therewith, feeding mechanism, a presser foot, a work support, a yielding member engaging the fabric in advance of the needles, said yielding member having ribs inclined rearwardly and away from the center plane passing between the needles.
7. A presser foot including a foot portion having two needle openings and an opening disposed in front of the needle openings, a yielding shoe mounted in said opening in front of the needle openings and having ribs formed thereon inclined rearwardly and away from a center plane passing between the needle openings.
8. A presser foot including a foot portion having two needle openings and an opening disposed in front of the needle openings, a yielding shoe mounted in said opening in front of the needle openings and having ribs formed thereon inclined rearwardly and away from a center plane passing between the needle openings, said presser foot having a keel located directly in front of said yielding member and disposed in said plane passing centrally between the needles.
9. A presser foot including a foot portion having two needle openings, and an opening in advance thereof, a bridge portion spanning said last named opening, a yielding shoe mounted in said last named opening, a stem attached to said shoe and extending up through said bridge portion, a spring attached to the upper end of said stem and normally depressing the shoe and limiting the downward movement thereof, said shoe having ribs on its under face inclined rearwardly and away from a plane passing centrally between the needle openings.
10. A presser foot including a foot portion having two needle openings and an opening in advance thereof, a bridge portion spanning said last named opening, a yielding shoe mounted in said last named opening, a stem attached to said shoe and extending up through said bridge portion, a spring attached to the upper end of said stem and normally depressing the shoe and limiting the downward movement thereof, said stem and normally depressing the shoe and limiting the downward movement thereof, said shoe having ribs on its under face inclined rearwardly and away from a plane passing centrally between the needle openings, each rib having its forward face substantially vertical and its rearward face inclined.
11. A presser foot including a foot portion having two needle openings and an opening in advance thereof, a bridge portion spanning said last named opening, a yielding shoe mounted in said last named opening, a stem attached to said shoe and extending up through said bridge portion, a spring attached to the upper end of said stem and normally depressing the shoe and limiting the downward movement thereof, said shoe having ribs on its under face inclined rearwardly and away from a plane passing centrally between the needle openings, each rib having its forward face substantially vertical and its rearward face inclined, said presser foot having a keel located in front of said shoe and in said plane passing between the needle openings.
12. The combination of a work support, feeding mechanism, a stitch forming mechanism, and a member engaging the fabric above the work support, said member having ribs arranged in advance of said stitch forming mechanism and so disposed as to stretch the fabric fed underneath the same by the feeding mechanism.
13. The combination of stitch forming mechanism, a feeding mechanism, a work support, a presser foot, and opposed sets of diagonal ribs at the front end of the presser foot coöperating with the feeding mechanism and to stretch the fabric prior to the stitching thereof.
14. The combination of stitch forming mechanism, a feeding mechanism, a work support, and means for holding the fabric against the work support including a member having sets of ribs one on each side of a center line extending parallel to line of feed, said ribs being disposed so as to stretch the fabric fed underneath the same by the feeding mechanism.
15. The combination of stitch forming mechanism, a feeding mechanism, a work support, a presser foot having a guiding fin at its forward end, and a yielding member carried by the presser foot to engage the fabric in the rear of the guiding fin and in advance of the stitching mechanism, said yielding member coöperating with the feeding mechanism and having ribs disposed so as to stretch the fabric prior to the stitching of the same.
16. The combination of a stitch forming mechanism, a work support, a feeding mechanism including a feed dog having spaced fabric engaging surfaces, a presser foot, a member engaging the fabric between the spaced fabric engaging surfaces and having sets of ribs disposed so as to stretch the fabric between said feed engaging surfaces.
17. The combination of stitch forming mechanism, a work support, a feeding mechanism including a feed dog having spaced fabric engaging surfaces, a presser foot, a

member engaging the fabric between the spaced fabric engaging surfaces and having sets of ribs disposed so as to stretch the fabric between said feed engaging surfaces,
5 said feed dog having its adjacent faces alongside of said feed engaging surfaces beveled.

In testimony whereof, I affix my signature in the presence of two witnesses.

NELSON D. CLARK.
